UNITED STATES PATENT OFFICE.

ROBERT M. KELLOGG, OF METUCHEN, NEW JERSEY.

DESIGN FOR A PIPE-REPAIR-SLEEVE MEMBER.

SPECIFICATION forming part of Design No. 35,327, dated November 26, 1901.

Application filed July 17, 1901. Serial No. 68,692. Term of patent 14 years.

To all whom it may concern:

Be it known that I, ROBERT M. KELLOGG, of Metuchen, New Jersey, have invented a new and original Design for a Pipe-Repair-Sleeve Member, of which the following description, in connection with the accompanying drawings, is a specification, like numerals on the drawings designating like parts.

My invention relates to repair-sleeves for pipes, in the configuration of which I have invented and produced a new and original design to be shown and described fully in the accompanying drawings and specification.

In the drawings, Figure 1 shows in plan and Fig. 2 in side elevation a pipe-repair-sleeve member in the construction of which my novel configuration is embodied.

The novelty of my design resides in the ensemble or appearance of my device in its entirety, salient points thereof being design-

nated by reference-numerals, of which the part marked 1 is an elongated semicylindrical body having lateral flanges 2, enlarged laterally near one end adjacent a deep swell 3, from which an inclined shoulder 4, grooved 25 at 5, leads to a constriction or throat portion 6, the opposite end of the sleeve member presenting a constriction 7 and groove 8.

Having thus described my invention, what I claim, and that on which I desire to secure 30 protection, is—

The design for a pipe-repair-sleeve member, substantially as shown and described.

In testimony whereof I have signed my name to this specification in the presence of 35 two subscribing witnesses.

ROBT. M. KELLOGG.
